UNITED STATES PATENT OFFICE.

LOUIS W. CARROLL, OF RIVERSIDE, ILLINOIS, ASSIGNOR OF ONE-HALF TO GLENN MUFFLY, OF CHICAGO, ILLINOIS.

STEAM-HEATING SYSTEM.

Original application filed January 3, 1925, Serial No. 406. Divided and this application filed December 23, 1926. Serial No. 156,680.

This invention relates to improvements in heating systems of the low pressure type, such as are employed for heating buildings, and the like, and is a division of application for a patent Serial No. 406, filed January 3, 1925, on steam heating system.

The main objects of this invention are to provide an improved furnace adaptable for closely regulated heating systems; to provide improved means for controlling the combustion and the water feed in a low pressure furnace; to provide improved means for regulating the water level in an open feed water tank in proportion to the vapor pressure in the furnace so that a constant water level is maintained in the boiler under the varying vapor pressures; to provide the improved means for indicating the pressure in the boiler; to provide an improved safety relief; to provide improved means for indicating the boiler water level; to provide improved means for controlling the combustion thru a wide range; and to provide a sensitive control operated by the vapor pressure for simultaneously controlling the feed water and the furnace combustion.

An illustrative embodiment of this invention is shown in the accompanying drawings, in which:

30 Fig. 1 is a general view of a system embodying the improvements provided in my invention as installed in a building.

Fig. 2 is a vertical sectional view of the furnace, showing the boiler feed and damper control features of this invention.

Fig. 3 is a section taken on the line 3—3 of Fig. 2.

Fig. 4 shows the upper end of the boiler with parts thereof in a changed position.

40 Referring to the drawings, the furnace 1 includes a combustion chamber 2 having grates 3, and a boiler or vaporizing space 4. The exhaust flue 5 leads out from the upper end of the combustion chamber 2 and a by-pass flue 6 is connected to the ashpit 7, below the grates 3, and joined into the exhaust pipe 5 forward of the hinged damper 8.

50 The vapor from the water space 4 passes out through the pipe line 9, which taps into the riser pipe 10, connected into the upper end of the water space 4. The pipe 9 leads throughout the building and distributes the heated vapor to the various radiators 11. In the system shown, a return piping 13 is pro-

vided for the radiators, and the condensed vapor flows back and discharges from the spill pipe 14 into the feed water tank 15. Since a certain amount of water is lost through leakage in the circulating system, or evaporation from the feed water tank, provision is made for automatically adding a compensating amount of water from the water line 16, which has an outlet 17 over the feed water tank.

Figures 2, 3 and 4 illustrate the method of obtaining a very sensitive and positive regulation of combustion in response to small variations of steam pressure, as is required especially in the type of heating systems shown, in which a close regulation of the steam or heat supply to each individual radiator is accomplished. Close regulation causes very sudden changes in the demands for heat placed upon the furnace, which demands are met by providing a very sensitive draft and feed water control.

In the form shown the controlling instrumentality comprises a manometer which may be a float or a bell 18, which is open at the bottom, and is suitably guided for free vertical movement within an open water tank 19. The bottom of the tank 19 is provided with an inwardly projecting portion 20, which extends into the bell 18, and to the upper end of which is connected the riser pipe 10 from the water space 4, which also serves to support the tank. The vapor or vapor pressure is admitted into the bell 18, and in passing around the outer edges condenses and provides a water seal. The height of the water 90 is governed by the height of the inner projection 20, since the water overflows over the top of the projection 20 and runs back into the boiler. The pressure in the boiler, usually a few ounces, causes a difference in the 95 water levels inside and outside of the bell, and the area of the bell provides sufficient power from the low unit pressure to operate the damper and feed water control.

Upward pressure on the bell 18, in excess of atmospheric pressure, rotates the lever 22 counter-clockwise. The lever 22 is fulcrumed at the bracket 23, secured to the wall of the tank 19, and is connected by means of a pivoted link 24 to the upper end of the float 18. On the opposite side of the fulcrum 23, the lever is connected by means of the rod 25 to the end of the crank arm 26 of the damper

shaft 27, which is rotatably mounted in the flue pipe 5.

In the raised or vertical position shown in Fig. 2, the damper 8 is vertical and obstructs 5 the passage in 5, closes the air inlet orifice 28 in the rear of the by-pass flue 6, and opens the flue 6 to the exhaust flue 5. This position effectually dampens the combustion on the grates 3, and the air which leaks into the ash- 10 pit is by-passed directly into the exhaust pipe.

In the lower position of the float 18, the damper 8 is positioned as shown in Fig. 4. In this position the exhaust flue 5 is unobstructed, and the by-pass pipe 6 is completely closed 15 to the flue 5. Also, the aperture 28 is open to the atmosphere and supplies fresh air to the grates 3 through the ashpit 7. These two positions provide for a zero draft and a maximum draft on the fire, and the intermediate positions of the damper will regulate 20 the combustion draft to any desired degree. A very slight fluctuation of the vapor pressure is sufficient to move the damper through the full arc of ninety degrees. The manifest differences between 25 this method of draft regulation and those in common use are that the mechanical parts are well balanced, and that resistance to the movement of the float 18 is practically constant for a considerable distance in its vertical travel. Such is not the case with the usual flexible pressure actuated diaphragms 30 which provide for very little movement and offer a widely varying resistance to the fluid pressure. By rotating the damper instead of lifting it, a large amount of the friction usually encountered, especially from the chains and cables which are arranged to operate over pulleys for the operation of such 35 dampers is eliminated. In this invention the resistance of the damper movement is reduced sufficiently so that it becomes practical to operate the dampers directly from the very low vapor pressures without introducing a 40 secondary source of power. The amount of water in the open receptacle 19 is self-regulating, as explained above, and the differences in the water levels will be only a few inches. A common working pressure for a 45 vapor heating system of this type is about four ounces per square inch. This produces a difference of about seven inches between the water levels. No additional safety valve is required in this arrangement, as the water 50 seal provides a very positive acting safety valve. The height of the drum 19 establishes a maximum steam pressure at which steam will escape through the water seal, and this pressure cannot be changed by the operator or by accidental means.

The products of combustion are drawn out from the passage 5, through the flues 29, which extend through the feed water tank 15 and connect into the chimney or stack at 30. 65 This arrangement serves to utilize the heat of

the exhaust gases for raising the temperature of the feed water in the tank 15. The pre-heating of the returned water by the flue gases and the sensitive control of the steam pressure in the boiler are important features 70 of the complete system, which is designed especially for use in connection with the combination steam and water radiators shown herein, and more fully described in my co-pending application, Serial No. 406, dated 75 January 3, 1925.

The returned water is spilled from the pipe 14 into the open feed water tank 15. This also allows any air in the return system 13 to escape. The tank 15 is connected from a point near the upper part of the tank to the lower portion of the water chamber 4 by means of the open pipe 31. Thus, the level of the water in the tank 15 is slightly higher than the level of the water in the boiler, which is under the pressure of the vapor. The water level in the tank 15 may be used as a guide for determining when additional water should be added to the system, thus saving 80 the cost of the usual water gage and eliminating the danger of broken gage glasses.

By providing a float 32 for controlling the outlet valve 33, in the end of the pipe 17, water is automatically added whenever the level falls below a predetermined point. This 95 makes the replenishing of water completely automatic.

Since the bell 18 moves in response to a very small difference in pressure, it prevents an excessive steam pressure and also eliminates the customary steam gage. Graduations placed upon a stationary sector 34, mounted on the tank 19, will indicate by the position of the pointed end 35 of the lever 22 the steam pressure more accurately than is 105 shown by the usual low pressure steam gages.

To improve the steaming qualities of the furnace and to keep a constant water level in the boiler, an interconnection between the rod 25 and the mechanism of the feed water float 32 is arranged to compensate for the variations in steam pressure, and thus provides a still more accurate control over the supply water to the system. A pin 36 on the rod 25 engages in the forked end of one arm of the bell crank lever 37. The lever 37 is pivoted at 38 to a fixed bracket 39, attached to the pipe 17. The downwardly extending arm of the bell crank lever carries the pivot pin 40 of the float lever 41. The rearwardly extending end 42 of the float lever 41 has an irregularly cam-shaped surface 43, bearing against the lower end of the stem of the supply valve 33. When the rod 25 is stationary, the float 32 falls with the lowering of water 110 in the reservoir 15 and opens the valve 33 to admit water from the supply pipe 17 until the water level is restored to the point where the float allows the valve 33 to close.

In the position shown in Fig. 2, the vapor 115

bell 18 is in the full upward position, and the difference between the water levels in the feed water tank and the boiler is at a maximum, since the vapor pressure in the boiler is 5 at the highest point. When the steam pressure falls and the bell 18 moves down to the lowest position, the rod 25, having the pin 36, is raised and moves the float pivot 40 nearer to the stem of the valve 33. This 10 changes the leverage of the float 32 on the valve 33, and also the shape of the cam surface 43 will allow the valve 33 to close at a lower level of water. It is evident that when the water in the tank 15 is replenished 15 during a period of low pressure in the boiler, the level in the feed water tank should be lower than if replenished during a high pressure. The ratios of the lever and the contour of the surface 43 are so designed that a practically uniform volume of water is maintained in the system, whether the boiler is 20 cold or under full pressure.

At a given steam pressure in the boiler, the level in the tank 15 will be at a given 25 height above the boiler water level. Hence, the gage 43, rigidly attached to the float 32 and coacting with the pointer provided by the inner end of the lever 37, will indicate very closely the water level in the boiler and 30 replace the customary water gages. The heating system is designed to operate with a practically constant steam pressure, there being only a slight difference between the maximum and minimum allowable pressures, but 35 there are differences in the boiler level and feed water tank level at the slightly different boiler pressures. This difference in level for indicating purposes is substantially compensated for by attaching the pointer to the 40 bell crank lever 37 and the gage to the float, as described.

I claim:

1. In combination, a furnace having a closed steam and water space, an open feed 45 water tank connected to said space, means for supplying water to the tank and means operated by the pressure in the space to control said means for varying the water level in the feed water tank as the vapor pressure in the said space varies so as to maintain a constant water level in said space at different vapor pressures.

2. In combination, a furnace having a closed steam and water space, an open feed 55 water tank connected to said space, and means controlled by the vapor pressure in said space for varying the height of the water in said tank to maintain the water level in said space constant at different vapor pressures 60 therein.

3. In combination, a furnace having a closed water vaporizing space; an open feed water tank connected to said space, a water supply pipe for the tank having a valve, a float in the tank for controlling the valve, and means actuated by vapor pressure in the said space for changing the relation of the float to the valve so as to provide a higher water level in the tank at high vapor pressures in 65 said space than at lower pressures in the 70 same.

4. In combination in a furnace having a closed water vaporizing space, a feed water tank connected with said space, a fixedly mounted valve for controlling the water supply to said tank, a pivotally mounted bell crank having a depending arm, a float pivoted on said arm and engaging with the valve, and means actuated by vapor pressure in the 75 said space for positioning the bell crank to regulate the action of the float upon said 80 valve.

5. In combination in a device of the class described, an open feed water tank, a bell crank having a pivot in fixed relation with the tank, said crank having a depending arm, a float pivotally mounted on said arm, a fixed water supply pipe having a valve controlled by the float, and means for positioning the bell crank to govern the relation between the 85 float pivot and said valve to change the water level at which the float will close the valve.

6. In a device of the class described, a boiler, an open feed water tank communicating therewith, an inlet valve for the tank, a float in the tank having a movable pivot and having an arm for actuating the valve, and means sensitive to pressure in said boiler for moving the said pivot to change the relation between said arm and the valve for regulating 90 the water level in the tank at which the float will close the valve.

7. In combination, a vaporizer having a combustion chamber provided with a grate in the bottom and a closed water vaporizing space around the combustion chamber; an outlet flue leading from the upper end of the combustion chamber; a by-pass flue leading from underneath the grate to said flue; an air inlet to the by-pass flue; a centrally pivoted damper for simultaneously controlling the outlet flue, the by-pass flue and said air inlet, in proper relation for controlling the amount of air drawn through the grate; and a float actuated by the vapor pressure in the 105 water space for controlling said damper.

Signed at Barcelona this 7th day of July, 110
1926.

LOUIS W. CARROLL.
